CLAIM

The ornamental design for a console for vehicle, as shown and described.

DESCRIPTION

FIG. 1 is a top view of a console for vehicle according to our novel design;

FIG. 2 is a front view of a console for vehicle according to our novel design;

FIG. 3 is a right side view of a console for vehicle according to our novel design, the left side view being mirror symmetrical to the right side view; and,

FIG. 4 is a front right elevational view of a console for vehicle according to our novel design.

The bottom and rear portions of the surface configuration of console for vehicle are not part of the claimed design.

The broken line showing of environmental structure and broken lines defining the boundaries of the top and rear side edges of the console are for illustrative purposes only and form no part of the claimed design.
